UNITED STATES PATENT OFFICE.

JOHN BIRT MUSE, OF CAMERON, NORTH CAROLINA.

AIR-HEATING DEVICE FOR SUPPLYING HEATED AIR TO BUILDINGS FOR CURING TOBACCO.

1,372,034.

Specification of Letters Patent. Patented Mar. 22, 1921.

Application filed October 8, 1919. Serial No. 329,260.

To all whom it may concern:

Be it known that I, JOHN B. MUSE, a citizen of the United States, residing at Cameron, in the county of Moore and State 5 of North Carolina, have invented certain new and useful Improvements in Air-Heating Devices for Supplying Heated Air to Buildings for Curing Tobacco, of which the following is a specification, reference being 10 had therein to the accompanying drawings.

This invention relates to a tobacco curing apparatus, and has for its object the improvement of the construction of a furnace and its coöperating parts, whereby a comparatively small furnace can efficiently heat 15 a large building by reasons of the novel structure of the furnace and its necessary coöperating pipes or flues.

Another object of the invention is the 20 production of a tobacco curing apparatus which will evenly distribute the hot air throughout the building by reason of the peculiar positioning of the pipes, as well as other peculiar construction.

With these and other objects in view, my 25 invention comprises certain other novel combinations, arrangements and constructions as will be hereinafter specifically described, illustrated in the accompanying drawings, 30 and more particularly pointed out in the appended claim.

In the drawings:

Figure 1 is a perspective view of the furnace or stove of my improved apparatus, 35 while—

Fig. 2 is a longitudinal section of the same.

Fig. 3 is a sectional view taken on the line 3—3, Fig. 2, and looking in the direction of 40 the arrows.

Fig. 4 is a section taken on the line 4—4, Fig. 2, looking in the direction of the arrows.

Fig. 5 is a plan view of the preferred embodiment of my apparatus.

Referring to the drawings by numerals, 1 designates a portion of a building in which 5 tobacco is to be stored for curing, and preferably at the front end 2 of the building 1 (Fig. 5) are positioned two furnaces 3. In Fig. 5 I have shown a diagram of two tobacco apparatuses, but it will only be necessary to specifically describe one, as they are substantially duplicates.

55 The furnace 3 comprises a body having

sides 4 and at the bottom of the body is formed an ash pit 5; the body (Fig. 3) is supported upon bricks 6. The sides 4, contiguous to the ash pit 5 are provided with inwardly extending flanges 7, which flanges 60 support grate bars 8. At the upper edge of each side 4 is an outwardly extending flange 9.

The top of the furnace comprises an inner curved plate 10 and an upper curved plate 65 11. The edges of the inner plate 10 rest upon the top of the sides 4, (Fig. 4) and the edges of the outer or upper curved plate 11 are flattened to form flanges 12, which flanges 12 fit snugly upon horizontal flanges 70 9 and these flanges are fastened together by suitable rivets or bolts 13. The outer plate 11 of the top of the furnace is corrugated, as at 14, intermediate its ends to provide a greater radiating surface. Between plates 75 10 and 11 is formed a hot air compartment 15. Near the front end of the outer plate 11 is an air inlet opening surrounded by a nipple 16 upon which is mounted a curved fresh air pipe 17, which pipe 17 is provided 80 with a suitable valve 18 for controlling the passage of fresh air into the hot air compartment 15.

A hot air pipe 19 has its inner end on a nipple on the top of the plate 11 near its 85 inner end within the building 1 and within the hot air pipe 19 is placed a plurality of small or auxiliary hot air pipes 20, which communicate with the compartment 15, the inner ends of some of the pipes 20 rest 90 against the top edge of the nipple engaged by pipe 19, and in the primary or outer pipe 19 are formed corresponding apertures 20^a, one being the outlet for each auxiliary pipe 20 (Figs. 1 and 2) so that hot air is passed 95 from the hot air compartment 15 through the auxiliary pipes 20 into the building at different points or locations, and some heated air is also discharged from the end of pipe 19, which end terminates short of the front 100 2 of the building 1, as shown in the diagram of the apparatus in Fig. 5.

The smoke pipe 21 is connected to the inner end of the body of the furnace and is extended to near the rear end of the building (Fig. 5) and then brought back to and extended through the front end 2 of the building, discharging into a suitable stack 22. This smoke pipe 21 also serves to heat some of the air in the building 1.

While I have described the preferred embodiment of my invention and have illustrated the same in the accompanying drawings, certain minor alterations or changes 5 may be found desirable in the extensive manufacture of my apparatus, and therefore, I reserve the right to make such alterations or changes as shall appear to one skilled in the art to which this invention 10 relates, and which fairly fall within the scope of the appended claim.

What I claim is:

A device of the kind described consisting 15 of a furnace provided with a top including a top plate having a nipple formed thereon, said furnace provided with a hot air compartment under said top plate, a fresh air

pipe communicating at one end with said hot air compartment, a curved or bent primary hot air pipe positioned at one end 20 upon said nipple, a plurality of auxiliary hot air pipes within said primary hot air pipe and filling the same and some having their inner ends resting against the top edge of the nipple, and said primary hot air pipe 25 having a number of side discharge openings or apertures corresponding to the auxiliary primary hot air pipes, each auxiliary pipe having its end communicating with a side opening, and the primary hot air pipe being 30 left free to discharge hot air near one end.

In testimony whereof I hereunto affix my signature.

JOHN B. MUSE.
